The ornamental design for an LED flare, as shown and described.

DESCRIPTION

The present Application is related to co-pending U.S. patent application Ser. No. 13/049,761, filed Mar. 16, 2011. The entirety of which is incorporated by reference in the present application.

FIG. 1 is a front view of the first image of a LED flare showing my design;

FIG. 2 is a top view of a second image thereof;

FIG. 3 is a bottom view of a third image thereof;

FIG. 4 is a side view of a fourth image thereof;

FIG. 5 is a back view of a fifth image thereof;

FIG. 6 is a perspective front view of a sixth image thereof; and,

FIG. 7 is a perspective back view of a seventh image thereof.
